UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

FILLING-END-RETAINING MEANS FOR WEFT-REPLENISHING LOOMS.

1,292,058.

Specification of Letters Patent. Patented Jan. 21, 1919.

Application filed September 17, 1917. Serial No. 191,671.

To all whom it may concern:

Be it known that I, ALONZO E. RHOADES, a citizen of the United States, residing at Hopedale, county of Worcester, State of Massachusetts, have invented an Improvement in Filling-End-Retaining Means for Weft-Replenishing Looms, of which the following description, in connection with the accompanying drawing, is a specification, 10 like characters on the drawing representing like parts.

This invention relates to weft replenishing looms preferably of the automatic type and its object is to provide means for catching and thus retaining the trailing end of the abandoned filling carrier after it is discharged from the shuttle in the operation of replenishment so that it will not be caught and carried by the shuttle or the fresh filling carrier into the cloth upon the succeeding pick.

This object is secured in the present invention by a mechanism mounted upon the lay and projecting beneath the shuttle box 25 into the path of the discharging filling carrier and also by the said mechanism in combination with additional means located on the usual chute down which the discharging filling carrier passes.

30 These and other objects of the invention will appear more fully from the accompanying description and drawings and will be particularly pointed out in the claims.

Figure 1 is an end elevation partially in 35 vertical cross section of so much of an automatic weft replenishing loom of the Northrop type as is necessary to a disclosure of the present invention with a preferred form of the said invention embodied therein;

40 Fig. 2 is a front elevation of the transfer end of the lay shown in Fig. 1 together with a portion of the picker, the picker guide, and the chute;

45 Fig. 3 is a detail in plan of a portion of the construction shown in Fig. 2.

The present invention is not concerned with the particular construction or operation of the general features of the loom to which it is applied. For convenience of 50 illustration the invention is shown in the preferred form selected as embodied in an automatic filling replenishing loom of the well known Northrop type.

In this type of loom the frame or loom 55 side 1 supports at the transfer end of the

loom a hopper stand 2 upon which is mounted a rotary hopper 3 carrying the supply of fresh filling carriers 4. The lay 5 carries at the transfer end the shuttle box 6 and the lay and shuttle box are provided with a vertical opening 7 therethrough to permit the downward discharge of an abandoned filling carrier when the shuttle is boxed at the transfer end of the loom.

A transerrer 8 is pivotally mounted on 65 the hopper stand and provided with a dog 9 which upon the call for filling replenishment is lifted into the path of a bunter 10 carried by the lay thus causing the transerrer to force a fresh filling carrier, in this 70 case a bobbin, from the hopper 3 into the shuttle and thereby discharge the abandoned or exhausted filling carrier or bobbin in the shuttle down through the opening 7.

The end of the filling extending from the 75 abandoned filling carrier through the eye of the shuttle is usually, in feeler looms, severed by suitable mechanism adjacent the nose of the shuttle and this severed end must be drawn back through the eye of the shuttle 80 and clear of the shuttle or it is liable to be caught by the shuttle or by the fresh filling carrier and dragged back into the shed and woven into the cloth causing an imperfection.

In this invention mechanism is provided 85 to catch and retain this filling end as the filling carrier is discharged from the shuttle and prevent it from being dragged back into the shed by the shuttle or the fresh filling carrier.

The main mechanism provided for this purpose is mounted on the lay and in the preferred form illustrated consists of a plate 11 having a serrated edge 12 with the serrations pointing away from the shed. This plate is slotted at 13 and secured to the lay by pins 14 passing through the slots, thus permitting the plate to move in and out or transversely upon the lay.

A lever 15 is fulcrumed upon a vertical pin 16 carried by the lay and at one end is pivoted at 17 to the plate 12 and at the other end 18 is curved to project slightly in front of the bunter 10 which may be notched or slotted as shown to receive this end of the lever. A spring 19 abuts a fixed portion of the lay and is seated in a socket 20 on the end 18 of the lever and thus acts normally to project the plate 11 rearwardly into the 110

opening 7 through which the discharged filling carrier passes.

The serrated edge of the plate 11 must project into this opening 7 in order that it 5 may catch and retain the trailing filling end. Preferably the plate must be movable to withdraw this serrated edge from the opening or otherwise it might be hit by the discharging filling carrier thus causing 10 damage and breakage of the parts. Preferably, therefore, means such as illustrated are provided for automatically withdrawing the plate out of the path of the discharging filling carrier.

15 It will be seen that when the call for replenishment takes place and the dog 9 is elevated and the lay beats up, the end 18 of the lever will be first struck by the dog 9 thus withdrawing the plate 11 from the 20 opening 7 just in time to get it out of the way before the transerrer 8 forces in the fresh filling carrier and thereby forces the abandoned filling carrier down through the opening 7. Immediately thereafter the lay 25 moves rearwardly, the dog disengages the bunter and the spring 19 acts to restore the plate 11 to its inwardly projected position and the trailing end of the filling drags over the serrated edge and is caught and retained thereby.

The mechanism thus described may be sufficient of itself to catch and retain the filling end so that it will not be caught and drawn back by the shuttle or the fresh filling carrier into the shed but in addition this invention provides in combination therewith filling retaining means on the upper edge of the chute which means in connection with other features is made the subject of an 35 other application Serial No. 191,673, filed 40 September 17, 1917.

45 The chute comprises a metal plate 21 pivotally mounted on a horizontal stud 22 carried by a bracket 23 secured to the loom side. The stud 22 is surrounded by a helical spring 24 connected at one end to the stud and at the other end to the plate and acting to swing the chute 21 yieldingly rearwardly.

50 The means for catching and retaining the filling carried by the upper edge of the chute is provided in the serrated edge 25 illustrated in which the serrations preferably point away from the shed.

55 The chute stands normally in the position illustrated in Fig. 1. As the lay beats up it contacts with the upper edge of the chute on the rear wall of the opening 7, the chute yielding to permit this contact. Upon 60 transfer taking place the filling carrier passing through the opening 7 contacts with the inclined chute 21 and is guided down thereby into a suitable receptacle. As the filling carrier passes down the chute the lay moves rearwardly and the trailing end extending

over the edge of the plate 12 next drags over the serrated edge of the chute which thus affords an additional means for catching and retaining the end and preventing it being drawn back into the shed.

70 Thus the present invention provides, either in the means specifically shown as the serrated edge of the plate mounted on the lay or in the combined means specifically shown as the serrated edge of the said plate 75 combined with the serrated edge of the chute, means for preventing the end of the abandoned filling carrier from being carried back by the shuttle or the fresh filling carrier into the shed.

80 Having fully described my invention, what I claim as new and desire to secure by Letters Patent is:

1. In a weft replenishing loom, a lay provided with a shuttle box and having an 85 opening therethrough to permit the discharge of the abandoned filling carrier, means mounted on the lay and projecting into said opening to catch and retain the trailing end of said filling carrier after it is 90 discharged, and means for temporarily withdrawing said catching means out of the path of the discharging filling carrier.

2. In a weft replenishing loom, a lay provided with a shuttle box and having an 95 opening therethrough to permit the discharge of the abandoned filling carrier, means mounted on the lay and projecting into said opening to catch and retain the trailing end of said filling carrier after it is 100 discharged, and means operated by or through the replenishing action of the loom temporarily to withdraw said catching means out of the path of the discharged filling carrier.

105 3. In a weft replenishing loom, a lay provided with a shuttle box and having an opening therethrough to permit the discharge of the abandoned filling carrier, means mounted on the lay and projecting 110 into said opening to catch and retain the trailing end of said filling carrier after it is discharged, and a chute located beneath said opening to receive and guide the discharged filling carrier and having its upper edge provided with filling retaining means to catch and retain the said trailing end.

115 4. In a weft replenishing loom, a lay provided with a shuttle box and having an opening therethrough to permit the discharge of the abandoned filling carrier, means mounted on the lay and projecting into said opening to catch and retain the trailing end of said filling carrier after it is 120 discharged, and a chute located beneath said opening to receive and guide the discharged filling carrier and having its upper edge serrated to catch and retain the said trailing end.

125 5. In a weft replenishing loom the combination

nation of features as set forth in claim 4 together with means acting to permit the said chute to contact with, and move forwardly upon the beat up of, the lay.

- 5 6. In a weft replenishing loom a lay provided with a shuttle box and having an opening therethrough to permit the discharge of the abandoned filling carrier, a plate provided with a serrated edge and
- 10 horizontally mounted on the lay with its serrated edge projecting into said opening to catch and retain the trailing end of said

filling carrier after its discharge, means for yieldingly projecting said plate rearwardly, and means operated by or through the re- 15 replenishing action of the loom for temporarily moving said plate forwardly to withdraw the serrated edge from said opening during the passage of the filling carrier therepast.

In testimony whereof, I have signed my name to this specification.

ALONZO E. RHOADES.
